SUSPENSION FOR LUMINESCENT TUBES

Jean Baptiste Joseph Marcel Abadie, Paris,
FranceApplication January 8, 1936, Serial No. 58,194
In France March 17, 1931

6 Claims. (CL. 177—352)

The present invention relates to improvements in suspensions for luminescent tubes and is a continuation in part of Patent No. 2,030,491 for Device for applying luminescent tubes to power transmission lines.

An object of the invention is to provide a means for attaching a luminescent tube directly to a power line, and for this end the suspension provides a yieldable support adapted for use with glass tubes.

A further object is to overcome the corrosive effect of the electric couple set up by contact of a suspension device with a power cable.

The above and other objects are accomplished in the forms of the device described herein and illustrated in the drawing wherein,

Figure 1 is a side elevation of a horizontal beacon light applied to a power cable, with the light and insulating structure shown in section.

Figure 2 is a side elevation of an application of the invention to a vertical beacon light, with the insulating structure partly broken away.

Figure 3 is an enlarged fragmentary view showing a modified hook in a section taken on the line 3—3 of Figure 1, and

Figure 4 is an enlarged fragmentary view showing a modified clamp in a section taken on the line 4—4 of Figure 1.

Beacon lamps of the type contemplated are of use in indicating the location of charged power lines and find particular application in pointing out such lines on air routes and near landing fields. The lamps are of the high tension gaseous discharge type, as explained in the parent application, hanging directly on the power cable and using for a ground connection an air discharge condenser or some body of lower potential, such as a parallel power line of low tension.

Referring now to Figure 1, 10 designates a power cable on which is hung a suspension frame composed of hooks 11 and connecting bar 12. The hooks are free to slide and turn on the cable, the extent of the motion being limited by a yielding attachment to the cable thru a clamping member 13 which is fastened on the cable by means of a clamping bolt 14, and coil springs 15 connecting the clamping member to the opposite ends of the connecting bar 12. The lamp structure is suspended from the opposite ends of the bar 12, additional yieldable suspension being provided by the short coil springs 16. The springs 15 and 16 are preferably made of an inoxidizable or difficultly oxidizable material as under the

influence of the conditions of use ordinary springs are of short duration.

The lamp consists generally in a hard glass outer tube 17 within which is located a tightly wound spiral gaseous discharge tube 18 having electrodes 19 at the opposite ends of the outer tube. One of such electrodes 19 is connected to the power line 10 by means of the conductor 20 which here serves also to connect that end of the lamp to the spring 16 on the frame. For complete insulation of this conductor and also to fix it securely against withdrawal the outer tube 17 and its arm 21 are filled with pitch 22 or the like. The other electrode 19 is connected to the leakage condenser 23 which discharges into the surrounding air, providing a ground for the lamp circuit. This end of the lamp is supported from the coil spring 16 thru the connecting bar 24 and is insulated from the power line 10 by the glass or porcelain insulator 25. The end of the tube is held in a metal ring 26 attached to the insulator 25, the ring also serving as a support for the leakage condenser 23. A water shed system is employed on these lamps to prevent accumulation of a short-circuiting water film on the outside of the tube. This system comprises in this case, bell-shaped hoods or covers 27 over the connectors between the power line and the tube, and the collar 28 on the outer tube 17. These members are provided with a water-repellent surface which breaks up the film of moisture and destroys the short circuit.

It has been learned from experience that where a lamp suspension of one metal hangs on a power cable of a different metal a destructive electrochemical action is set up resulting in damage to the cable. The present invention contains a remedy for this condition by providing hooks and clamp of the suspension of the same metal as the cable wherever practical. Where it is not practical to form the hook or clamp of this metal it is advantageous to insert into the portion touching the cable a liner of the metal of the cable. Figures 3 and 4 illustrate the use of such liners. The liners are merely inserted in the ordinary parts of the suspension as they are applied to the power cable.

Figure 3 is a detail showing a modification of the hook 11. These hooks are bent by hand to conform to the cable 10 and so make a snug fit. 50 A lining strip 29 is inserted in the bend of the hook to avoid setting up a couple between the hook 11, which is usually of a hard metal such as iron or steel and the cable 10 which will ordinarily be of copper or aluminium. The liner 29

will be of the same material as the cable, so that the couple will be between the hook and the liner and the power cable will not be subjected to the corrosive effect of the couple. It may, in some instances, be practical to make the hooks of the same material as the power carrier and in such a case no lining is needed.

The clamping member 13, as seen in Figure 4, consists of two plates 30 bent to fit the power cable 10 and held together at their lower edges by suitable bolts or rivets 31 which serve also as fastenings for the springs 15. The upper edges of the plates are held together by a clamping bolt 14. The clamp 13, as the hooks 11, is provided in this modification with a lining strip 29 to break up the couple at the cable surface.

Figure 2 illustrates a form of the suspension adaptable to vertical beacons. The lamp comprises the outer tube 17, the spiral discharge tube 18, the electrodes 19, the leakage condenser 23 and the protecting cover 32. The cover 32 serves to protect the condenser 23 from short circuiting water and is provided with a watershed surface. In this form the suspension comprises two clamping members 33 to which is secured the tube holder 34. The clamping members 33 are similar to the clamping plate 14 and are constructed of front and back plates connected by bolts or rivets. If the material of the clamp is different than that of the power cable 10, the liners 29 will be inserted to break up the couple at the surface of the cable.

With reference again to the suspension in Figure 1, it will readily be seen that the light suspended is completely yieldable. Under the force of wind it can swing about the cable and can also slide along the cable in either direction. The checking action of the springs is yielding and free from shock which would tend to fracture the glass tubes. In general the use of these beacon lights is such as to subject them to considerable strain from wind and storm. High tension power lines are usually high above the earth and run through open country being thereby exposed in a particular manner to the effects of the weather.

It is obvious that various changes and modifications may be made in the details of construction and design of the above specifically described embodiment of this invention without departing from the spirit thereof, such changes and modifications being restricted only by the scope of the following claims:

1. A device for suspending beacon lights from power cables comprising a frame, means for

movably mounting said frame on the cable, means fixed on the cable, yieldable means for connecting said frame to said fixed means for restricting the extent of movement of said frame, light holding means, and yieldable means for connecting the light holding means to the frame to permit further movement of the light beyond the extent of movement of the frame.

2. A device for suspending beacon lights from power cables comprising a bar parallel to the cable, spaced hooks rigid with the bar and hooked on the line for movably securing the bar to said line, a checking clamp fixed on said cable intermediate said hooks, springs connecting the ends of the bar to said clamp to hold said bar 15 yieldingly from movement, and further springs at the opposite ends of the bar to support the light.

3. A device for suspending beacon lights from power cables comprising a frame having a bar 20 parallel to the cable and spaced cable engaging hooks on the bar bendable to the shape of the cable, to support the frame movably from the cable, a clamping member adapted to be fixed on said cable, yieldable connecting means between 25 said frame and said member to limit the extent of movement of said frame, and light holding means on the frame.

4. A device for suspending beacon lights from power cables comprising a frame having a bar 30 parallel to the cable and spaced cable engaging hooks on the bar bendable to the shape of the cable to provide a movable support for said frame, means including yieldable connecting means between 35 said frame and said cable yieldably to restrict movement of the frame on the cable, and light holding means on the frame.

5. A device for suspending beacon lights from power cables comprising a frame, means for movably mounting said frame on the cable, means 40 including yieldable means for restricting the extent of movement of the frame on the cable, light holding means, and means for yieldably suspending said light holding means from said frame to permit yielding vertical movement of the light 45 and additional horizontal movement thereof beyond the extent of movement of the frame.

6. A device for suspending beacon lights from power cables comprising a frame, movable holding means on the cable adapted to hold said frame 50 movably on said cable, fixed means including an elastic connection on the cable for yieldably restricting the extent of movement of said frame, and light holding means on said frame.
